UNITED STATES PATENT OFFICE.

HOWARD HUGHES, ARTHUR FERGUSON, AND HARRY L. LOWE, OF CLINTON, INDIANA.

SWITCH FOR INDUSTRIAL-RAILWAY TRACKS.

1,114,883.

Specification of Letters Patent.

Patented Oct. 27, 1914.

Application filed January 5, 1914. Serial No. 810,450.

To all whom it may concern:

Be it known that we, HOWARD HUGHES, ARTHUR FERGUSON, and HARRY L. LOWE, citizens of the United States, residing at Clinton, in the county of Vermillion and State of Indiana, have invented a new and useful Switch for Industrial-Railway Tracks, of which the following is a specification.

10 The present invention appertains to railway switches, and aims to provide a novel and improved switch adapted particularly for use in mine or industrial railway tracks.

The present invention contemplates unique 15 means for mounting a switch piece or tongue for oscillatory movements, whereby the switch piece or tongue will properly coöperate with the end of the corresponding rail.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

The invention has been illustrated in its 30 preferred embodiment in the accompanying drawing, wherein:—

Figure 1 is a plan view of the switch, somewhat diagrammatical in nature. Fig. 2 is a perspective view, on an enlarged 35 scale, of one of the switch pieces or tongues. Fig. 3 is a similar view of the other switch piece or tongue and its bearing. Fig. 4 is an enlarged perspective view of one of the 40 bearings for the switch pieces. Fig. 5 is a similar view of one of the supporting members for the switch pieces.

In the accompanying drawing, there is illustrated in Fig. 1, an ordinary switch layout of a mine or industrial railway track. 45 The numerals 1 and 2 designate the rails of the main track, while the numerals 3 and 4 designate the rails of the switch or side track. The rail 3 extends toward, but terminates short of, the main rail 1, while 50 the rail 4 is connected to the rail 2 of the main track, the section or portion 2^a of the rail 2 between the switch rails 3 and 4 extending toward but terminating short of the end of the rail 4.

55 In carrying out the present invention, suitable switch pieces or tongues 5 and 6

having their butt ends arranged adjacent or abutting against the ends of the rails 2^a and 3 and have their tips or points arranged to engage the respective rails 1 and 2 in the usual manner. The switch pieces 5 and 6 are provided with inwardly projecting, downwardly offset ears 7 adjacent their free ends, which ears are pivoted to an underlying cross bar 8 which is adapted 65 to be actuated by the usual switch stand, or its equivalent.

As a means for supporting the switch pieces 5 and 6 for oscillatory or vibratory movements, elongated plates or castings 9 are disposed on the tie underlying the switch pieces, and are provided at their outer or remote ends with upwardly offset tongues or lips 10 overlapping the inner base flanges of the rails 1 and 4. The plates 70 or castings 9 are also provided with spike notches 11 in their side edges and inner ends, for securing the plates upon the tie underneath the switch pieces. The plates 9 are also provided with longitudinal upstanding ribs 12 extending away from and flush with the tongues or lips 10, and the switch pieces 5 and 6 are slidable upon the ribs 12, whereby the switch pieces will be properly supported at their two positions. 75 The tongues or lips 10 overlapping the base flanges of the rails, will also assist in holding the rails in place upon the ties.

Coming to the salient or cardinal feature of the present invention, which resides in 80 the means for mounting the switch pieces for oscillatory movements, and for holding the ends of the switch pieces and corresponding rails in abutment properly, there is provided for each switch piece, a bearing 95 plate 13 resting upon that tie underlying the butt end of the switch piece and the end of the rail against which the switch piece abuts. The bearing plate 13 is provided at one end with an upstanding semi-circular seat 14 100 which is provided at its upper edge with an inturned flange or lip 15.

Each of the switch pieces has its butt end rounded, as at 16, to fit snugly against the end of the corresponding rail, and each 105 switch piece is also provided with a depending shank or stem 17 at its butt end. The lower ends of the shanks or stems 17 are provided with outturned arcuate flanges 18, which extend through an arc slightly over 110 degrees.

The bearing plates 13 are so arranged,

that the seats 14 are disposed adjacent the switch pieces, and the shanks or stubs 17 of the switch pieces engage within the flanges or lips 15 while the flanges 18 rest snugly upon the bearing plates 13 and engage under the flanges or lips 15 to bear snugly against the seats 14. In this manner, the switch pieces 5 and 6 are pivotally connected to the bearing plates 13, it being noted that the flanges 18 of the switch pieces may be readily inserted longitudinally under the flanges or lips 15 of the bearing plates, against the seats 14.

The bearing plates 13 are provided with notches 19 at their side edges for the engagement of the spikes which secure the bearing plates to the underlying tie.

The bearing plates 13 are provided with means for accommodating or receiving the ends of the rails 2^a and 3, whereby the ends of the said rails will be held in co-operative relation with the switch pieces. To this end, the plates 13 are provided with longitudinal open slots 20 intermediate their side edges and extending away from the seats 14, and the plates 13 are cut away or recessed as at 21, below and at the sides of the slots 20. Thus, the slots 20 are arranged to receive the webs of the rails 3 and 2^a while the cut away portions or recesses 21 are adapted to receive the terminal portions of the base flanges of the said rails.

In assembling the switch pieces and their bearing plates with the ends of the rails 2^a and 3, the switch pieces are first applied to the plates 13 by slipping the flanges 18 of the switch pieces into engagement with the seats 14 of the bearing plates. Then, the bearing plates 13 may be engaged with the ends of the rails 3 and 2^a, by slipping the slots 20 of the bearing plates into engagement with the webs of the said rails, and then by securing the bearing plates 13 upon the underlying tie, the base flanges of the rails will be received or accommodated by the recesses 21 of the bearing plates 13. As a consequence, the butt ends of the switch pieces will be held in abutment with the ends of the rails 3 and 2^a, and cannot be accidentally detached without the separation of the bearing plates and rails 3 and 2^a. It is to be observed that the butt ends of the switch pieces are rounded to snugly engage the ends of the rails 3 and 2^a and to permit the switch pieces to oscillate properly as the switch throw bar 8 is reciprocated.

When the interlocking portions of the switch pieces and their bearing plates are slipped longitudinally into engagement, and when the bearing plates are assembled with the ends of the rails 3 and 2^a, the switch pieces will be permitted to oscillate, but will be locked against rearward or upward movement by the rails 3 and 2^a.

65 From the foregoing, the advantages and

capabilities of the present invention will be obvious to those versed in the art, without further comment being necessary.

Having thus described the invention, what is claimed as new is:—

1. In a device of the character described, a bearing and a switch piece, the bearing and switch piece having portions adapted to be interlocked by a longitudinal movement, and the bearing being applicable to the end of a rail whereby the switch piece will abut thereagainst and will be retained in engagement with the bearing.

2. In a device of the character described, a bearing and a switch piece, the butt end of the switch piece and the bearing having portions adapted to be interlocked by a longitudinal movement, the bearing having means for receiving the end of a rail whereby the butt end of the switch piece will abut thereagainst and whereby the switch piece and bearing will be held in engagement.

3. In a device of the character described, a bearing plate having a curved seat, and a switch piece having a curved portion at its butt end engageable with the said seat, the said portion and seat being interengageable by a longitudinal movement, and the bearing plate being applicable to the end of a rail to bring the butt end of the switch piece against the end of the rail and to hold the said curved portion engaged to the said seat.

4. In a device of the character described, a bearing plate having an arcuate seat, and a switch piece having a curved portion engageable with the said seat by a longitudinal movement, the bearing plate having means extending from the said seat for receiving the end of a rail whereby the end of the rail will hold the curved portion of the switch piece engaged to the said seat.

5. In a device of the character described, a bearing plate having an arcuate seat, the seat having an inturned lip, and a switch piece having a stub to engage the said lip, the stub having a flange to engage the said seat under the said lip.

6. In a device of the character described, a bearing plate, and a switch piece, the bearing plate and butt end of the switch piece having interengaging portions, and the bearing plate having an open slot to engage the web of a rail.

7. In a device of the character described, a bearing plate, and a switch piece, the bearing plate and butt end of the switch piece having interengaging portions, the bearing plate having an open slot to engage the web of a rail, and a cut away portion below the said slot for receiving the base flange of the rail.

8. In a device of the character described, a bearing plate having an arcuate seat, an open slot extending away from the said seat to receive the web of a rail, and a recess be-

low the said slot for receiving the base flange of the rail, and a switch piece having a curved portion to slip longitudinally into engagement with the said seat.

- 5 9. In a device of the character described, a bearing plate having a curved seat and an open slot extending away from the said seat to receive the web of a rail, the said seat having an inturned lip, and a switch piece
10 the butt end of which has a stub engageable

with the said lip, the said stub having an arcuate flange engageable with the said seat under the lip.
